UNITED STATES PATENT OFFICE

THOMAS HARDING, OF NEWARK, NEW JERSEY, ASSIGNOR TO J. L. SOMMER MANUFACTURING COMPANY, A CORPORATION OF NEW JERSEY

DESIGN FOR A BEVERAGE SPOON OR SIMILAR ARTICLE

Application filed July 8, 1931. Serial No. 40,435. Term of patent 14 years.

To all whom it may concern:

Be it known that I, THOMAS HARDING, a citizen of the United States, and a resident of Newark, in the county of Essex and State of New Jersey, have invented a new, original, and ornamental Design for a Beverage Spoon or Similar Article, of which the following is a specification, reference being had to the accompanying drawings, forming part thereof.

Figure 1 is a plan view of a beverage spoon or similar article showing my new design, and

I claim:

The ornamental design for a beverage spoon or similar article, as shown.
